LAMP HOLDER

Leonard Atkin, Bloomfield, N. J., assignor to Stone Manufacturing Co., a corporation of New Jersey

Application March 21, 1955, Serial No. 35,114

Term of patent 14 years

(Cl. D48—20)

FIG. 1.

FIG. 2.

FIG. 3.

I claim:

The ornamental design for a lamp holder, substantially as shown.
